Primary Examiner — Marie D. Fast Horse(74) *Attorney, Agent, or Firm* — Whitaker Chalk Swindle & Schwartz PLLC; Charles Gunter(57) **CLAIM**

The ornamental design for a ceiling fan, as shown and described.

DESCRIPTION

FIG. 1 is a bottom perspective view of a ceiling fan showing my new design;

FIG. 2 is a front elevation view of the ceiling fan of FIG. 1; FIG. 3 is a rear elevation view of the ceiling fan of FIG. 1; FIG. 4 is a right side view of the ceiling fan of FIG. 1; FIG. 5 is a left side view of the ceiling fan of FIG. 1; FIG. 6 is a top plan view of the ceiling fan of FIG. 1; FIG. 7 is a bottom plan view of the ceiling fan of FIG. 1; and, FIG. 8 is a top perspective view of the ceiling fan of FIG. 1. The cross-hatch pattern which is fragmentarily shown in the figures is understood to repeat uniformly and continuously across the entire indicated blade areas.

The broken lines in the drawings depict a portion of the ceiling fan that forms no part of the claimed design.
